SPECTACLE CASE

Robert G. De Weese, Rochester, N. Y., assignor to Shuron Optical Company, Inc., Geneva, N. Y., a corporation of New York

Application May 7, 1956, Serial No. 41,367

Term of patent 14 years

(Cl. D57—1)

FIG. 1.

FIG. 2.

FIG. 3.

FIG. 4.

FIG. 5.

FIG. 6.

Fig. 1 is a front view of a spectacle case embodying my new design;

Fig. 2 is a rear view thereof;

Fig. 3 is a side view of the spectacle case looking at one side thereof;

Fig. 4 is a side view looking at the opposite side of the spectacle case;

Fig. 5 is a top view of the spectacle case; and
Fig. 6 is a bottom view thereof.

I claim:

The ornamental design for a spectacle case, as shown.
